(57) **CLAIM**

The ornamental design for a bin as shown and described.

DESCRIPTION

FIG. 1 is a top front perspective view of a bin showing our new design;

FIG. 2 is a top rear perspective view thereof;

FIG. 3 is a front elevational view thereof;

FIG. 4 is a rear elevational view thereof;

FIG. 5 is a right side elevational view thereof, the left side elevational view being identical;

FIG. 6 is a top plan view thereof; and,

FIG. 7 is a bottom plan view thereof.

The broken lines depict portions of the bin that form no part of the claimed design.

1 Claim, 5 Drawing Sheets
